PLAY PILL KIT

Albert M. Steiner, Cincinnati, Ohio, assignor to Par Beverage Company, Cincinnati, Ohio, a corporation of Ohio

Application December 2, 1954, Serial No. 33,371

Term of patent 7 years

(Cl. D34—15)

Fig. 1

The opposite side of the article, not shown, has substantially the same appearance as the side shown in Figure 1. Portions of the drawing figures are diagonally lined to indicate transparency.

I claim:

The ornamental design for a play pill kit, substantially as shown and described.
